FIG.1

FIG.2

INVENTOR:
Svante Verner Holm
By Mr. Wallace White
ATTY.

UNITED STATES PATENT OFFICE.

SVANTE VERNER HOLM, OF STOCKHOLM, SWEDEN.

DEVICE FOR THE CARRYING OF CURTAIN RODS AND THE LIKE.

1,355,974.

Specification of Letters Patent.

Patented Oct. 19, 1920.

Application filed April 3, 1919. Serial No. 287,324.

To all whom it may concern:

Be it known that I, SVANTE VERNER HOLM, a subject of the King of Sweden, residing at St. Eriksgatan 16, Stockholm, Sweden, in the Kingdom of Sweden, have invented certain new and useful Improvements in Devices for the Carrying of Curtain Rods and the like, of which the following is a specification.

10 The present invention has for its object devices for the carrying of curtain rods, poles for draperies, and the like.

In the round curtain rods now used, which are provided with round or spherical knobs at the ends, esthetic considerations demand that the heads of the holders carrying the rods shall entirely, or apparently entirely, surround the rod. In such hitherto used holders the head consists of an entire ring 20 which is formed of one piece with the holder, which is usually screwed in the wall. The taking down of curtain rods together with the curtain is a somewhat troublesome process.

25 The object of the present invention is to render possible an easy and convenient fixing and taking down of the curtain rods, although the heads of the holder entirely surround, or appear entirely to surround, the rod. For this purpose the heads surrounding the curtain rod are, in accordance with the present invention, constructed in the form of a jacket surrounding the outer end of the support, and composed of two parts 30 hinged with one another (or lockable with one another), of which the one is attached to the support, while the other is detachable or hinged in such a manner that when the said part is removed from its normal position surrounding the curtain rod, the curtain rod can be freely placed in, or removed from, the holder.

In order to make plain the invention there is shown in the accompanying drawing a 45 form of the device in question.

Figure 1 shows the device in lateral view and Fig. 2 shows it in front view. 1 designates the actual attachment for the support 2 which attachment consists of a clamp-like part, suitably made of a tin plate bent double, and equipped with a vertical channel in which the support 2 can be adjustably inserted by tightening the screws 3, by means of which the clamp-like part is fixed 55 to the window frame or to the wall. These

screws pass through the parts lying over one another of the clamp-like part, which parts thus, by the tightening of the screws are jammed against one another, so that the channel carrying the support 2 is pressed 60 together and jammed around the support, which in cross section suitably has a rectangular or other non-round shape, in order that the arrangement may be firm. The support is furnished at the top with a horizontally, or mainly horizontally, projecting arm 4, which at its outer end is bent into a hook 5, to which the head carrying the curtain rod 14, and divided into two parts 5, 7, hinged together, so that they may be turned with 65 regard to each other, is fixed. The one half 7 of this head is shown in Fig. 1, by lines composed of dots and dashes in an opened position and united by means of the hinge 8 with the part 6 fixed to the hook 5. When 70 the part 7 is lowered in its normal position, it is held securely in this position by means of some locking device suitable for the purpose, for example by a catch formed at the end of the hook, which catch 9 on the lowering of the part 7 engages a corresponding part in the part 7. It should be obvious that 75 the curtain rod 14 with the curtains fixed to it can by the use of this device be easily brought into its position on the curtain 80 holder 4, or removed from it, without its being necessary for any parts to be loosened or for the curtain to be dislodged from its position.

10 and 11 designate holders for rods 15, 90 carried by the support 2, or by the latter's horizontal arm 4 by the aid of a socket 12, or a movably arranged arm 13, fixed to the said parts, which holders are intended to carry inner curtains.

95 As shown by the drawing, the part 6, which forms one half of the head, is constructed in the form of a plate jacket surrounding the hook 5, and thus forms a covering for the hook 5. Hereby is attained the 100 advantage that the entire support 2 can be made of for example iron or other comparatively cheap material, whereas the head, which even when the curtain is fixed up, is 105 visible and forms a decorative part of the device, may be made of other more expensive material, such as brass, or the like.

The esthetic requirements are thus very well provided for by this arrangement without its being necessary for the entire sup- 110

port to be made of such expensive material. The part 7 is also made of the same material as the part 6. By the locking device 9 is attained the advantage that the part 7 can be 5 locked to the part 6 in such a manner that joints between the parts in question, which spoil the appearance, are obviated. It should be obvious that the support 2 can be made also in the other ways than that shown 10 here by way of example.

Having thus described my invention, I declare, that what I claim is:

1. A device for supporting curtain rods, comprising a supporting member, a semi-circular rod-carrying member inclosing a 15 portion of said supporting member and secured thereto, and a corresponding semi-circular member hinged to said rod-carrying

member and coöperating therewith to form a ring.

2. A device for carrying curtain rods and the like, comprising a supporting member, a semi-circular rod-carrying member inclosing a portion of said supporting member and attached thereto, and a corresponding semi-circular member hinged to said rod-carrying member, the end of the supporting member being adapted to project into said last member thereby to lock the same to the rod-carrying member.

In testimony whereof I have affixed my signature in presence of two witnesses.

SVANTE VERNER HOLM.

Witnesses:

ALMA POTTORSEN,
AUG. HAGELIN.
